UNITED STATES PATENT OFFICE.

HENRY H. BONNEY, OF FAIRMONT, MINNESOTA.

MOP-CABINET.

SPECIFICATION forming part of Letters Patent No. 735,700, dated August 11, 1903.

Application filed March 18, 1903. Serial No. 148,364. (No model.)

To all whom it may concern:

Be it known that I, HENRY H. BONNEY, a citizen of the United States, residing at Fairmont, in the county of Martin and State of Minnesota, have invented certain new and useful Improvements in Mop-Cabinets; and I do hereby declare the following to be a full, clear, and exact description of the invention, such as will enable others skilled in the art to 5 to which it appertains to make and use the same, reference being had to the accompanying drawings, and to the figures of reference marked thereon, which form a part of this specification.

15 This invention relates to a wall-cabinet for holding a mop; and the object of the invention is to produce a cabinet in which a wet mop may be hung out of sight to drain and dry.

20 A further object is to provide a cheap receptacle of the kind stated having means for holding the mop-cloth out of contact with the handle and also having a tank to receive the drippings from the mop.

25 In the accompanying drawings, Figure 1 is a front view of the device with the door open and the mop hanging in place. Fig. 2 is a side elevation with the door closed. Fig. 3 is a perspective view showing the inside of 30 the frame on which the mop hangs, and Fig. 4 is a horizontal section looking down.

Speaking generally, the device comprises a casing adapted to be hung on the wall and having a drip-tank at the bottom, a swinging frame in the casing to support the mop and inclose the mop-cloth, and an outer door or cover to inclose and conceal the mop-head.

35 Referring specifically to the drawings, 6 indicates the back board of the casing, which 40 is secured to the wall by screws at top and bottom.

7 indicates the sides of the casing. These sides are perforated, as at 7^a, to permit a circulation of air through the casing to dry the 45 mop-cloth.

8 is a drip-tank, preferably formed of metal, at the lower end of the casing to receive the drippings from the mop-cloth, and this tank may be emptied as occasion requires by re- 50 moving the plug 8^a.

The hanging frame for the mop comprises

a partition 9, preferably formed of metal, hinged at 9^a to one side of the casing and having at top and bottom wooden cross pieces or cleats 10, which are notched to receive the 55 mop-handle, (indicated at 11.) These cleats are on the outside of the partition, and when the mop is placed within the cabinet the mop-cloth hangs on the inside of the partition and the mop-handle on the outside. The cloth 60 and handle are thus separated, so that the handle will not be wet and dirty and so that the drippings will drop into the tank. At the free vertical edge of the partition is a swinging leaf 12, which I will call a "gatherer," the 65 function of which is to gather any strings or loose ends of the cloth into the casing when the hanging frame is closed, thereby preventing the loose ends from being caught between the frame and the side of the casing when the 70 frame is closed. This leaf or gatherer is hinged to the free edge of the partition and operates automatically with the closing of the frame by means of a trip 13, which projects from the leaf in position to strike a post 14, 75 secured to the casing. When the frame of the partition is closed, the trip strikes the post and operates as a lever to turn the gatherer in, which thus carries with it the mop-cloth and prevents the latter from catching between 80 the partition and the side of the casing.

An outer inclosing door is indicated at 15. This is semicylindrical in shape to afford a recess for the mop-head and to give an ornamental appearance. The top 16 closes against 85 the back board and the bottom 17 against the tank. The bottom is notched for the mop-handle, which hangs therethrough. A latch for the door is indicated at 18. This is preferably a socket-latch let into the side of the 90 casing, having no projections on which the mop-cloth might catch.

In use, the door being opened, the hanging frame is swung out and the mop hung thereon with the cloth on the inside of the partition and the handle on the outside thereof, as shown in the drawings. When the partition is swung to, the gatherer tucks in all loose ends of the cloth, which then hangs over the tank, and any drippings therefrom fall into 100 the tank. The door is then closed, whereby the mop is held and concealed.

What I claim as new, and desire to secure by Letters Patent, is—

1. A mop-cabinet comprising a casing having a tank at the bottom thereof, a partition across the casing over the tank, and a mop-hanger on the partition.
2. In a mop-cabinet, the combination with a casing, of a swinging frame therein, a projecting leaf hinged to the free edge of the frame, and means to swing the leaf within the casing when the frame is closed.
3. A mop-cabinet comprising a casing hav-

ing a door, a tank at the bottom of the casing, a swinging partition in the casing above the tank, and means on the partition to hang a 15 mop with its cloth on one side of the partition and its handle on the other.

In testimony whereof I affix my signature in presence of two witnesses.

HENRY H. BONNEY.
